SHUTTLE CHANGER LOOM

Application filed June 11, 1931. Serial No. 543,645.

This invention relates to improvements in shuttle changer looms and it is the general object of the invention to provide means to prevent rebounding of a shuttle which falls by gravity to transfer position.

In a type of shuttle changing loom which has gone into use there is provided a magazine for supplying shuttles of two different types of filling. A common transfer position is provided and the shuttles from the rear stack are pushed to this position while the shuttles of the front stack fall one by one to the position. I find that there is an occasional tendency for the falling shuttles to rebound so that they are not in proper position to be transferred to the lay when the latter is ready to receive them. The discharge of the falling shuttles is regulated by a pair of devices one of which lies under and acts to release the lowest shuttle of the stack and the other of which moves into frictional holding engagement with the shuttle immediately above to hold the remainder of the stack in position. This second device insures the retention of the upper shuttles and provides room below the stack for the entry of a guard or the like which moves over a shuttle which has moved to transfer position to resist upward rebounding movements thereof. The first of the devices which normally supports the stack of shuttles is located so as to retain the lowest shuttle somewhat above the guard, the effect of this relation being to permit the shuttle to start its downward movement before engaging the yielding guard. The spring which holds the latter in position is therefore acted upon by the force of a moving shuttle and does not tend to resist or retard the latter to any appreciable extent.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a front elevation of a magazine of a two-cell shuttle changing loom made according to my present invention,

Fig. 2 is a vertical detailed section on line 2-2 of Fig. 1, showing the gravity feeding stack with all shuttles supported out of transfer position, and

Fig. 3 is a view similar to Fig. 2, but with a gravity feed shuttle in transfer position, the guard being positioned to prevent upward movement of the shuttle so placed.

Referring to the drawing the lay 10 may be provided with stationary binder 11 which defines part of the shuttle box on the lay to receive fresh shuttles. The magazine M may have front and rear partitions 12 and 13, respectively, between which lies a thin web 14 to define with said partitions front and back compartments 15 and 16, respectively. The rear compartment is supplied with reserve shuttles which do not primarily co-act with the subject matter of this invention. The lowest shuttle of this rear stack may be positioned by a plunger 17 which moves forwardly over a fixed plate 18 to push a shuttle on to a movable platform 19.

The shuttles of the front cell are concerned more particularly with the present invention and they are designated herein as S, S' and S2. A shaft 20 is pivoted to the front of the magazine frame and has mounted thereon a retaining hook 21 and a friction holder 22, the former extending downwardly and being secured to the shaft by a set screw 23 and the latter being loosely mounted on the shaft 20 and urged in a direction toward shuttle S' by means of a torsion spring 24 interposed between said device 22 and a fixed collar 25 on the shaft.

When the parts are in the position shown in Fig. 2 the hook 21 will lie under all of the shuttles in the forward stack and a connection between the bottom hook and the friction device 22 will serve to hold the friction surface 26 of the latter spaced from the shuttle S'. The spring 27 surrounding shaft 20 tends normally to hold the hook 21 in the position shown in Fig. 2. A wire 28 is operatively connected to an arm 29 secured to the shaft 20 and is effective when lifted to rock the hook 21 from the normal position shown in Fig. 2 to the position shown in Fig. 3. This movement of the hook is accompanied by a corre-

sponding movement to the left of the device 22 so that the latter moves into engagement with the shuttle S' to support the latter and all shuttles thereabove in substantially the relation shown in Fig. 3. It is to be understood that as soon as the hook 21 moves downwardly out of holding relation with respect to the shuttle S, the latter will drop to the movable platform 19. By means of devices not set forth herein and forming no part of the present invention said platform 19 is moved rearwardly to permit the shuttle S to drop on the lay.

The matter thus far described of itself forms no part of my present invention and is set forth herein for the purpose of illustrating one use of my invention.

In carrying my improvement into effect I employ a pair of levers 40 and 41 each pivotally mounted on a shaft 42 which happens to be present in the type of loom to which my invention is particularly adaptable. The upper arm 43 of each lever receives the outward thrust of a light compression spring 44 interposed between said arm and the magazine frame M. The lower part of the lever is provided with a downwardly and rearwardly inclined surface 45 which is rounded as at 46 and terminates in approximately a vertically extending surface. The rounded part 46 normally extends into the path of the shuttle S and is below the latter as shown in Fig. 2. When the shaft 20 rocks as hereinbefore described to move hook 21 from under the shuttle S the latter will start its downward movement and will be in motion when the front lower edge thereof strikes the rounded surface 46. The springs 44 will therefore be opposed to the weight of a moving shuttle and will have very little if any effect in retarding the latter. The ends 46 of the levers do not move very far, assuming the dotted line position shown in Fig. 3, until the shuttle S reaches the platform 19. Any rebounding which may have been caused on the part of the levers by engagement thereof with the bottom edge of shuttle S will have been checked by the spring before the top edge of the shuttle passes below the levers and for this reason the flat horizontal bottom 47 of the levers 40 will be in position to move over the upper front edge of the shuttle as soon as the latter passes thereunder. Any tendency on the part of shuttle S to rebound upwardly from the platform 19 will be checked by the bottoms 47 of the levers 40 and other mechanism not shown herein but essential in the completion of the shuttle changing operation may act immediately without waiting for the shuttle to find its position or without danger of crushing the shuttle because it is not properly positioned when acted upon by such devices.

From the foregoing it will be seen that I have provided a simple device to prevent rebounding of the shuttles in the front cell of a

shuttle changing magazine. It will also be seen that the movable support for the lowest shuttle of the stack normally holds the latter in a position above the rebound preventer so that the shuttle is permitted to get into motion before being required to press the preventer outwardly. It will also be seen that the friction device 22 serves to hold the next lowest shuttle in the stack sufficiently above the bottom ends of the levers 40 so that the latter can move over the lowest shuttle without interference.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom having a cell down which reserve shuttles feed by gravity and a lay to receive a reserve shuttle, a platform on which the shuttles fall in the course of their changing movement from the cell to the lay, and yielding means projecting into the pathway of a falling shuttle located above the platform to engage the top of a shuttle on the platform and prevent substantial upward motion of the shuttle.

2. In a shuttle changing loom having a cell down which reserve shuttles feed by gravity and a lay to receive a reserve shuttle, a platform on which the shuttles fall in the course of their changing movement from the cell to the lay, means to hold a stack of shuttles above the platform so that the bottom of the lowest shuttle in the stack is farther above the platform than the height of the shuttle, and a yielding device located between the said bottom of the lowest shuttle in the stack and the platform to engage the top of a shuttle falling onto the platform and prevent substantial upward movement thereof.

3. In a shuttle changing loom having a cell down which reserve shuttles move by gravity and a lay to receive a reserve shuttle, a platform on which the lowest shuttle in the cell falls preparatory to movement to the lay, means to support the shuttles in the cell so that the bottom of the lowest shuttle is normally above the platform, and a yielding rebound preventer normally projecting into the path of a shuttle moving from the supporting means to the platform, said preventer located to engage a shuttle moving onto the platform at a point below the bottom of the lowest shuttle in the stack and above the platform by a distance equal substantially to the height of the shuttle, the shuttle moving to the platform acquiring momentum before engaging the rebound preventer to cause the latter to yield.

4. In a shuttle changing loom having a cell down which reserve shuttles move by gravity and a lay to receive a reserve shuttle, a plat-

form on which the lowest shuttle in the cell falls preparatory to movement to the lay, and means to project into the path of movement of the shuttle after the latter has reached the 5 platform to engage the shuttle and prevent upward rebounding thereof.

In testimony whereof I have hereunto affixed my signature.

AUGUSTIN J. CHEVRETTE.
